J. L. Wright
WITNESS:

UNITED STATES PATENT OFFICE.

GEORGE BAILEY, OF FORT WILLIAM, ONTARIO, CANADA.

TIE.

Application filed April 12, 1923. Serial No. 631,642.

To all whom it may concern:

Be it known that I, GEORGE BAILEY, a subject of the King of Great Britain, residing at Fort William, in the Province of Ontario and Dominion of Canada, have invented new and useful Improvements in Ties, of which the following is a specification.

This invention relates to railway ties and has for an object the provision of a reinforced composition tie, wherein the reinforcing means is arranged to support the load to which the tie is subjected and to distribute said load throughout the tie, so that excessive vibration is eliminated and danger of damage due to the passage of trains, is reduced to a minimum.

With the above and other objects in view, the invention further includes the following novel features and details of construction, to be hereinafter more fully described, illustrated in the accompanying drawings and pointed out in the appended claims.

In the drawings:—

Figure 1 is a side elevation of a tie constructed in accordance with the invention.

Figure 2 is a top plan view of the same.

Figure 3 is a transverse sectional view.

Figure 4 is a similar view taken on a different plane.

Figure 5 is a fragmentary vertical longitudinal section.

Figure 6 is a detail view of one of the reinforcing members.

Figure 7 is a section on the line 7—7 of Figure 6.

Figure 8 is a fragmentary plan view of the reinforcing member shown in Figures 6 and 7.

Figure 9 is a detail perspective view of one of the rail clamps.

Figure 10 is a fragmentary plan view of another reinforcing member.

Referring to the drawings in detail wherein like characters of reference denote corresponding parts, the body 10 of the tie which may be formed of concrete or other suitable composition, is reinforced throughout its length by means of horizontally arranged upper and lower metallic rods 11 and 12 respectively. These rods are preferably of rectangular cross sectional shape and have extending from diametrically opposite sides thereof ribs or flanges 13.

The upper surface of the body 10 is provided with seats 14 for the reception of

plates 15, preferably formed of hard wood and upon which the rails 16 are adapted to rest. The rails are preferably secured in place by means of clamps 17 which are provided with openings 18 for the passage of bolts 19. These bolts extend downwardly through openings provided in the tie and are surrounded by sleeves 20.

These sleeves are embedded in the tie and act to prevent vibration due to the passage of cars over the rails and thus reduce liability of damage to the tie. The lower ends of the bolts 19 are provided with heads 21.

Extending downwardly from the rod 11 and upwardly from the rods 12 are oppositely extending transversely and longitudinally inclined rods or arms 22. The ribs or flanges 13 of the reinforcing rods are formed integral therewith and the arms or rods 22 are provided by slitting these ribs or wings 75 transversely inward as indicated at 23 and longitudinally as shown at 24. The rods or arms 22 are inclined in opposite directions, that is, the rods or arms 22 of the reinforcing rods 12 are inclined oppositely with respect to the rods or arms 22 of the reinforcing rod 11 so that a truss-like formation is provided as shown in Figures 1, 2 and 5 of the drawings. The upper ends of the inclined arms 22 terminate just short of the upper surface of the tie, while the inclined arms of the reinforcing rod 11 terminate just short of the bottom surface. The truss-like formation thus provided will act to effectually reinforce the tie structure and reduce vibration to a minimum, so that danger of damage to the tie due to this cause will be correspondingly reduced.

Positioned beneath the plates 15 are reinforcing members 25. These members 25 are preferably formed of expanded metal and extend immediately beneath the plates 15 and downward along opposite sides of the tie as shown at 26. They thus provide a support for the plates 15 beneath the point of greatest strain.

The invention is susceptible of various changes in its form, proportions and minor details of construction and the right is herein reserved to make such changes as properly fall within the scope of the appended claims.

Having described the invention what is claimed is:—

1. A railway tie comprising a concrete

body, horizontally spaced upper and lower longitudinally disposed reinforcing rods embedded therein and located on different vertical and horizontal planes and vertically 6 and oppositely inclined rods extending from opposite sides of each of the horizontal rods and defining a truss-like formation.

2. A railway tie comprising a concrete body, horizontally spaced longitudinally 10 disposed reinforcing rods embedded therein, longitudinal ribs extending from opposite sides of the rods in the same horizontal plane and vertically and oppositely inclined rods extending oppositely and outwardly 15 from the ribs and defining a truss-like formation.

3. A railway tie comprising a concrete body, horizontally spaced longitudinally disposed reinforcing rods embedded therein, 20 horizontally disposed longitudinal ribs extending along opposite sides of the rods and said ribs having substantially L-shaped slits

extending inwardly from their outer side edges to provide upwardly inclined arms.

4. A reinforcing member comprising a 25 relatively heavy rod, ribs extending longitudinally of the rod on opposite sides thereof and said ribs having longitudinal and transverse slits extending inwardly from their side edges to provide relatively long angularly disposed arms.

5. A railway tie comprising a concrete body, horizontally spaced longitudinally disposed reinforcing rods embedded therein, vertically and oppositely inclined rods extending from the horizontal rods and defining a truss-like formation and horizontally disposed reinforcing members extending transversely across and downwardly upon 35 opposite sides of the tie.

In testimony whereof I affix my signature.

GEORGE BAILEY.
